(57) **CLAIM**

The ornamental design for a display screen with graphical user interface, as shown and described in the accompanying figures.

DESCRIPTION

FIG. 1 is a front view of a display screen with a graphical user interface showing our new design; FIG. 2 is a front view of a second embodiment thereof; and, FIG. 3 is a front view of a third embodiment thereof. The broken lines in FIGS. 1 through 3 showing the display screen and the remainder of the graphical user interface form no part of the claimed design.

The CaloriePUMPTM trademark which forms no part of the claimed design is a registered trademark of HOIST FITNESS SYSTEMS, INC.
